(57) **CLAIM**

The ornamental design for a portion of a toothbrush head, as shown and described.

DESCRIPTION

FIG. 1 is a front-right perspective view of a toothbrush head according to our design;

FIG. 2 is a left-front perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof;

FIG. 8 is a bottom view thereof; and,

FIG. 9 a close-up view of area IX of FIG. 3.

The portions of the toothbrush head shown in broken lines form no part of the claimed design. The greyscale shading depicts surfaces having the contrast in appearance shown.

1 Claim, 8 Drawing Sheets
